UNITED STATES PATENT OFFICE

153,290

DESIGN FOR A BALL POINT PEN

Anker W. Jensen, Oak Park, Ill.

Application January 13, 1947, Serial No. 136,123

Term of patent 7 years

(Cl. D74—17)

To all whom it may concern:

Be it known that I, Anker W. Jensen, a citizen of the United States of America, residing at Oak Park, in the county of Cook, State of Illinois, have invented a new, original, and ornamental Design for Ball Point Pen, of which the following is a specification, reference being made to the accompanying drawing, forming part thereof.

Referring to the drawings, Fig. 1 is a side elevational view of a ball point pen embodying my new design;

Fig. 2 is a front view; Fig. 3 is a rear view with the point in retracted position; Fig. 4 is a bottom view and Fig. 5 is a top view of the same.

The essential features of my design for a ball point pen reside in the transparent non-remov-

able cap slightly overlapping the barrel, in combination with the configuration, all as illustrated.

I claim:

The ornamental design for a ball point pen, substantially as shown and described.

ANKER W. JENSEN.
